WHISTLING SIGNAL FOR FLUID DELIVERY HOSE

Filed Oct. 28, 1936

UNITED STATES PATENT OFFICE

2,090,226

WHISTLING SIGNAL FOR FLUID DELIVERY HOSE

Walter T. Oxley, Fergus Falls, Minn.

Application October 28, 1936, Serial No. 107,993

6 Claims. (Cl. 226—66)

My invention provides an extremely simple and highly efficient device adapted for attachment to the discharge nozzle or end of a liquid delivery pipe to indicate when a receptacle has been filled to the maximum point of safety, and, generally stated, the invention consists of the novel devices and combinations of devices hereinafter described and defined in the claims.

More particularly, the invention is designed for application to and used in connection with the nozzles of gasoline discharge pipes such as used in filling automobile tanks. The signalling device is in the nature of a whistle connected with a source of air supply under light pressure and attached to the discharge nozzle of the gasoline delivery hose. Such nozzles are usually in the form of flexible tubes capable of being bent to the best form for insertion into the neck of gasoline tanks; and in the application of the whistling attachment thereto, the air tube connected for delivery to the whistle is also a flexible structure such as a small rubber hose, the receiving end of which is connected to the source of air supply and is also flexible.

The present invention is in the nature of a modification of or improvement on the "Whistling attachment for fluid delivery hose" disclosed and claimed in my pending application Serial No. 53,455, filed December 9, 1935 and allowed Sept. 8, 1936 and now Patent Number 2,063,696.

A preferred form and application of the invention is illustrated in the accompanying drawing wherein like characters indicate like parts throughout the several views.

Referring to the drawing:

Fig. 1 is a view chiefly in side elevation showing the whistling attachment applied to the flexible discharge nozzle of a gasoline hose with the nozzle positioned for delivery into the receiving neck of a gasoline tank, such as an automobile tank; portions of the tank being broken away and parts shown being in section;

Fig. 2 is a plan view showing the nozzle with some parts broken away;

Fig. 3 is a view partly in elevation and partly in section on the line 3—3 of Fig. 1;

Fig. 4 is a section on the line 4—4 of Fig. 3; and

Fig. 5 is a section on the line 5—5 of Fig. 3.

In Fig. 1 the numeral 6 indicates the receiving neck portion of a gasoline tank such as employed in automobiles, the numeral 7 indicates the rigid metallic tubular portion, and the numeral 8 the flexible portion of the gasoline discharge nozzle

which, as customary, receives the gasoline from the rubber hose or the like, not shown in the drawing. In the rigid section 7 of the nozzle is the customary normally closed check valve mechanism 9 which is adapted to be opened by upward pressure on a valve operating trigger 10, shown as mounted in a yoke 11 secured to said section 7.

In the structure illustrated, the nozzle is provided with a rigid metallic nozzle tip 12 which, in practice, will be inserted directly into the receiving neck 6 or the like of the gasoline tank or receiving receptacle.

The nozzle attachment proper includes a whistle that is located within and attached to the interior of the nozzle tip 12 and receives air under pressure from a flexible air supply tube 13 that is extended through the flexible portion 8 of the nozzle and out through one side of the rigid portion 7 of said nozzle. At the exterior of the rigid section 7 the flexible air tube 13 is connected to a valve casing 14 that is rigidly secured to said section 7 and receives air under pressure from a flexible hose or tube 15 that leads from a suitable source of air pressure, and, as shown, through a coupling 16 to which a pressure gauge 17 is applied. At the point of junction of tube 15 with coupling 16 is a stop cock 18 that is adapted to be opened and closed, at will.

The valve mechanism in casing 14 may be of any suitable form but, as illustrated and preferably, is of a type wherein the valve is normally closed but is adapted to be opened, at will, by pressure on the head 19 of the valve stem 20.

The body 21 of the whistle is preferably a metallic tube having a whistle opening 22 and a grooved core 23. The nozzle tip 12 is cut away to expose the whistle opening 22 and is provided with an inwardly pressed portion 24 that forms a seat for the discharge end of the whistle tube 21. The whistle tube 21, positioned as best shown in Fig. 3, is rigidly secured by solder, brazing or otherwise so that it will maintain the position in which it is located. Here it is important to note that the open end of the whistle tube 21 is located considerably above or backward of the delivery end of the nozzle tip 12.

The use and operation of the device described are substantially as follows: The nozzle tip 12 will be placed in the neck 6 of the receiving tank, considerably farther down than shown in Fig. 1, and so that the lower end of whistle tube 21 will be approximately at the maximum desired level of the gasoline or fluid to be delivered into the tank. To render the attachment operative, valve 55

18 must be first opened, but that will not deliver air to the whistle. To deliver air to the whistle, in addition to opening the valve 18, valve 19—20 must be depressed so as to permit a discharge 5 of air to the whistle. As long as the liquid in the tank does not close the lower end of whistle tube 21 whistle will not be sounded, but when the liquid reaches the maximum or desired level, it will close the lower end of whistle tube, thereby causing 10 the air, under increased pressure, to be discharged through whistle opening 22, which causes sounding of the whistle.

In practice, only a very low air pressure has been found necessary to cause sounding of the 15 whistle when and only when the lower end of whistle tube 21 is liquid sealed. In fact, about one pound of pressure is found the best for the purpose.

With the device described, the whistle and connections along the gasoline or fluid discharge nozzle are made through the latter, and hence, are protected against obstructions and leave the nozzle to be operated in the usual way, free from encumbrances. Of course it will be understood 25 that the whistle will be sounded, as above stated, upon the liquid sealing the lower end of the whistle if and only when the valve 20 is opened by pressure on its head 19. This valve head 19 is so located that it is within easy reach of the 30 thumb of the hand that grips the nozzle body 7 with the fingers in position to operate trigger 10.

If desired, instead of using a normally closed valve in casing 14, any other suitable form of valve such, for example, as the stop cock or valve 35 18, may be employed. However, the arrangement of the air valve in association with the valve operating trigger has many advantages and is thought to be preferable.

From the foregoing it will be understood that 40 the device described is capable of modification within the scope of the invention herein disclosed and claimed.

What I claim is:

1. The combination with a fluid delivery nozzle 45 comprising a rigid upper section, a tubular delivery tip and an intermediate flexible portion, of a whistle having a tubular body located within and attached to said nozzle tip and having a whistle opening exposed for discharge of air at 50 the exterior of said nozzle tip, the lower end of said tubular whistle being normally open, and an air tube extended through the rigid upper section and flexible section of said nozzle and attached to the upper end of said whistle tube. 55 2. The structure defined in claim 1 in which the open lower end of the whistle tube is mate-

rially above the open delivery end of said nozzle tip and said nozzle tip below the open end of said whistle tube is open for the flow of fluid therethrough.

3. The structure defined in claim 1 in which the open lower end of the whistle tube is materially above the open delivery end of said nozzle tip and said nozzle tip below the open end of said whistle tube is open for the flow of fluid therethrough, said nozzle tip having an inwardly 10 pressed semi-tubular portion that forms an extension of the whistle tube and opening at the exterior of the nozzle tip.

4. A nozzle adapted for application to the delivery end of a flexible hose, a whistle applied to said nozzle and movable therewith, said whistle having a normally open lower end located near to the normally open delivery end of said nozzle, and an air supply tube applied to said nozzle and connected to said whistle, whereby said nozzle and whistle are made portable as a common unit, 15 said nozzle being provided at its upper end with a flow control valve, and said air tube being provided with a valve located at the exterior of the valve-equipped end of said nozzle and from thence 20 extended through the interior of the nozzle and connected to the whistle tube within the tip of the nozzle.

5. A nozzle adapted for application to the delivery end of a flexible hose, a whistle applied to said nozzle and movable therewith, said whistle having a normally open lower end located near to the normally open delivery end of said nozzle, and an air supply tube applied to said nozzle and connected to said whistle, whereby said nozzle and whistle are made portable as a common unit, 25 said nozzle being provided at its upper end with a flow control valve, and said air tube being provided with a valve located at the exterior of the valve-equipped end of said nozzle and from thence 30 extended through the interior of the nozzle and connected to the whistle tube within the tip of the nozzle, the intermediate portion of said nozzle and said air tube being flexible.

6. A nozzle of the kind described having a 45 valve-equipped upper end and a tubular discharge tip at its lower end, a whistle located within said nozzle tip, said nozzle tip having lateral openings, one below the lower end of the whistle and the other at the whistle opening of 50 said whistle, and an air tube extended through the nozzle to the upper end of the latter and at the exterior thereof having a control valve, the entire device being portable as a unit.
